GARMENT HANGER

Ralph LaRue DuBois, 4242 E. 111th St.,
Tulsa, Okla. 74136

Filed Nov. 13, 1972, Ser. No. 305,939

Term of patent 14 years

Int. Cl. D6—08

U.S. Cl. D6—248

FIG. 1

FIG. 3

FIG. 1 is an elevational view taken from one side of a garment hanger showing my new design, a portion of one end being broken away for convenience of illustration, the opposite side being a mirror image of the side shown;

FIG. 2 is a top plan view thereof; and

FIG. 3 is an end elevational view thereof.

The bottom being planar and unornamented.

I claim:

The ornamental design for a garment hanger, substantially as shown and described.
